STROBOSCOPIC APPARATUS FOR CALIBRATING TIME INDICATING DEVICES

Joseph M. Weinberger, Brooklyn, N. Y.

Application April 4, 1952, Serial No. 280,486

5 Claims. (Cl. 73—6)

This invention relates to apparatus for calibrating precision instruments, and more particularly to calibrating timing instruments such as clocks and watches.

An object of this invention is to provide apparatus of the above mentioned character by means of which the oscillating parts of a watch or clock to be calibrated are stroboscopically compared with similar parts of a standard watch or clock.

Another object of this invention is to provide apparatus which compares these oscillating parts by direct observation of the instrument to be calibrated.

A further object of this invention is to provide apparatus whereby the instrument to be calibrated may be regulated while being intermittently illuminated and observed without resorting to phase-shifters and the like.

A further object is to provide apparatus for calibrating clocks and watches of an inherent accuracy comparable to the accuracy of the instrument to be calibrated, without utilizing any external controlling apparatus.

A still further object is to provide apparatus for intermittent views of substantially short duration of alternate half-cycles of oscillation of the observed oscillating member of the instrument to be calibrated to eliminate the ambiguous criteria due to apparent displacement of the stroboscopically produced images during successive half-oscillations.

A feature of this invention resides in the manner of intermittently illuminating the oscillating member of the instrument to be calibrated.

A further feature of this invention resides in the manner of spacing the intervals of intermittent illumination.

A still further feature of this invention resides in the manner of avoiding completion of the triggering circuit during alternate half-oscillations of the standard oscillating member.

Other objects and features will become apparent from the following descriptions and the accompanying drawing in which like numerals indicate similar parts, and in which:

Fig. 1 is a diagrammatic view of the mechanical and electrical portions of an embodiment of this invention,

Fig. 2 is a cross sectional view of the oscillating mechanism and a diagrammatic view of the contacting mechanism,

Fig. 3 is an enlarged view of the deflecting wedge showing the positions of the resilient member during each half-cycle of oscillation, and

Fig. 4 is a schematic view of a circuit adapted to produce intermittent illumination of substantially short duration.

The former practice in watch or clock calibration has been to illuminate the oscillating parts of these instruments by means of flashing lights controlled by means of electronic or rotating mechanical equipment, and the error determined by means of external devices such as phase-shifters and the like.

These methods have proven inadequate in that these devices were inherently inaccurate, difficult to control and very expensive to manufacture.

These previous devices were negative in operation, since the amount of error was to be determined by shifting the phase between the flashing light and the observed timepiece, and then attempting to make a proper amount of adjustment to the timepiece while it was removed from the device. This operation of trial and error may be repeated a number of times before a close approximation of correct regulation is reached, resulting in a lengthy and cumbersome operation.

The present invention provides a device of positive operation wherein the error is observed directly without any ambiguous criteria and immediately corrected while the timepiece is being observed in the device, thus resulting in rapid calibration of the observed instrument.

To properly calibrate a watch or clock of precise manufacture, requires a standard of equal or higher accuracy against which it can be compared.

This invention provides a device of such accuracy by utilizing the inherent, self-controlled accuracy of an oscillating system, such as a balance wheel of a watch or clock, without resorting to expensive and cumbersome controlling devices and which may be manufactured at substantially small cost.

In its simplest embodiment, this invention comprises an oscillating balance wheel 1, having a hairspring 2, a roller 3 and a deflecting wedge 4 which is maintained in oscillatory motion by a mainspring and barrel 5, a gear train 6 and an escapement 7. A pillar plate 8 and bridge 9 support the balance wheel assembly.

The hairspring 2 is attached at one of its ends to the staff 11 of the balance wheel 1 and, at its other end, to the bridge 9, and is regulated by means of a pair of regulator pins 10 which restrain the motion of the hairspring. The deflecting wedge 4 is attached to the roller 3 and subtends a substantially small angle from the axis of rotation of the balance wheel 1.

Attached to the pillar plate 8 and electrically insulated therefrom by means of an insulator block 28 is a resilient member 12 and a contactor member 13, also electrically insulated from the pillar plate 8 and from the resilient member 12.

Electrical contact is made with the pillar plate 8 by means of connection 14 and with the contactor member 13 by means of connection 15.

The source of intermittent illumination shown in this embodiment is an internally triggered, cold cathode, inert-gas-filled electronic flash lamp 16 which is energized by means of an electronic circuit 17. This circuit is described more particularly hereinbelow.

The connections 14 and 15, and the members 4, 12 and 13, comprise the triggering mechanism which sets off the action of the flash lamp 16 and provides the intermittent illumination which is directed toward the oscillating member 25 of an instrument to be calibrated.

The mainspring 5 is wound up and the balance wheel 1 is caused thereby to be rotated about its axis by means of the escapement 7, carrying along with it the deflecting wedge 4, which engages and deflects the resilient member 12 at substantially the time during which the balance wheel 1 is receiving its impulse from the escapement 7, thus insuring a minimum of interference with the motion of the balance wheel and promoting greater accuracy of the device.

When the balance wheel 1 is rotating in one direction (i. e., in Fig. 3 shown as counter-clockwise) the deflecting wedge 4 causes the resilient member 12 to assume the position 12a and to deflect toward the contactor member 13, briefly completing the electrical contact from

the connection 14, through the pillar plate 8, the bridge 9, the hairspring 2, the deflecting wedge 4, the resilient member 12, the contactor member 13 and to connection 15, thus triggering a flash of intermittent illumination of the flash lamp 16, by means of the electronic circuit 17. As the balance wheel 1 rotates farther, the deflecting wedge 4 releases the resilient member 12, breaking the electrical contact and insuring against any spurious and undesired flashes.

When the balance wheel 1 is rotating in the opposite direction (i. e., clockwise), the deflecting wedge 4 causes the resilient member 12 to assume position 12b and to deflect away from the contactor member 13, and no electrical contact is made.

It is to be noted that the deflecting wedge 4 engages the resilient member 12 at a time when the balance wheel 1 is moving at its greatest angular speed. In this manner, the duration of contact is extremely short and the instant of flash is accurately determined. This obviates the possibility of spurious flashes which would make a device of this kind difficult, if not impossible, to use as an accurate calibrating device.

Thus, the electrical circuit is completed during alternate half-cycles of oscillation of the balance wheel 1, when it is rotating in a counter-clockwise direction.

In Fig. 4, an electronic circuit is shown which comprises a voltage doubler circuit having rectifiers 18 and condensers 19, a charging circuit having a condenser 20, a resistor 26 and a voltage divider 21, an internally triggered, cold cathode, inert-gas-filled flash lamp 16 and a triggering circuit having resistors 22 and 23 and condenser 24. Connections 14 and 15 are connected respectively to the pillar plate 8 and the contactor member 13 as hereinbefore described.

The flash lamp 16 flashes at a rate determined by the period of oscillation of the balance wheel 1 and intermittently illuminates the oscillating member 25 of an instrument to be calibrated, which is viewed directly or through an optical system 27.

When the oscillating member 25 is synchronized with the balance wheel 1, it will appear to remain substantially stationary, while being observed under the intermittent illumination of the flash lamp 16. An apparent rotation of the oscillating member 25 in either direction indicates an out of synchronism condition which is rapidly corrected by means of the regulator provided in the instrument to be calibrated, which is adjusted until the apparent rotation has stopped.

Many mechanical faults of the instrument to be calibrated can be diagnosed by observing the characteristics of the apparent rotation of the oscillating member 25.

A set of indicating hands 30 moving at different speeds may be attached to the gear train to check the accuracy of the standard instrument on a calibrated dial 29 by observing the positions of the said hands and comparing them with another timepiece.

In other embodiments of this invention, the escapement 7 and the oscillating assembly may be driven directly by a mainspring or other source of rotary power without the use of intermediate gears.

The deflecting wedge 4 may be attached to any part of the balance wheel assembly or may be made integral therewith.

I wish it distinctly understood that, while I have particularly described the simplest elements adapted to perform the functions set forth, it is obvious that they could be subject to modifications, and various changes in form, proportion and in minor details of construction may be resorted to without departing from the spirit or sacrificing any of the principles of the invention.

What I claim is:

1. An apparatus for calibrating time indicating devices comprising an oscillating member, a flash lamp for intermittently illuminating an instrument to be calibrated, a circuit for momentarily energizing said flash lamp, a de-

flecting wedge electrically connected to and moving with said oscillating member and comprising one leg of a trigger circuit of said flash lamp energizing circuit, a resilient member adjacent said oscillating member, and a contactor member adjacent said resilient member and comprising the other leg of said trigger circuit; said resilient member and said contactor member normally forming part of an open circuit; said deflecting wedge positioned to engage said resilient member in substantially a period of maximum angular speed of said oscillating member and adapted to deflect said resilient member away from said contactor member during one half-cycle and to deflect said resilient member to momentarily touch said contactor member during a predetermined angular displacement of said oscillating member in the other half-cycle of oscillation of said oscillating member to close the said trigger circuit in response to said alternate half-cycles of oscillation and to disengage said resilient member after said predetermined angular displacement to break electrical contact between said wedge and said resilient member before electrical contact is broken between said resilient member and said contactor member.

2. An apparatus for calibrating time indicating devices comprising an oscillating member, spring means for storing power to impart oscillatory motion thereto, a flash lamp for intermittently illuminating an instrument to be calibrated, a circuit for momentarily energizing said flash lamp, a deflecting wedge electrically connected to and moving at the same speed as said oscillating member and comprising one leg of a trigger circuit of said flash lamp energizing circuit, a resilient member adjacent said oscillating member, and a contactor member adjacent said resilient member and comprising the other leg of said trigger circuit; said resilient member and said contactor member normally forming part of an open circuit; said deflecting wedge disposed to engage said resilient member in substantially a period of maximum angular speed of said oscillating member and adapted to deflect said resilient member to touch said contactor member during a predetermined angular displacement of said oscillating member in alternate half-cycles of oscillations of said oscillating member and close the said trigger circuit in response to said alternate half-cycles of oscillation and to disengage said resilient member after said predetermined angular displacement to break electrical contact between said wedge and said resilient member before electrical contact is broken between said resilient member and said contactor member.

3. An apparatus for calibrating time indicating devices comprising an oscillating member, spring means for storing power to impart oscillatory motion thereto, speed reducing means and escapement means to cooperate with said oscillating member to impart oscillatory motion thereto, a flash lamp for intermittently illuminating an instrument to be calibrated, a circuit for momentarily energizing said flash lamp, a deflecting wedge electrically connected to and moving with the same speed as said oscillating member and comprising one leg of a trigger circuit of said flash lamp energizing circuit, a resilient member adjacent said oscillating member, and a contactor member adjacent said resilient member and comprising the other leg of said trigger circuit; said resilient member and said contactor member normally forming part of an open circuit; said deflecting wedge disposed to engage said resilient member in substantially a period of maximum angular speed of said oscillating member and adapted to deflect said resilient member to touch said contactor member during a predetermined angular displacement of said oscillating member in alternate half-cycles of oscillation of said oscillating member and close the trigger circuit of said flash lamp energizing circuit in response to said alternate half-cycles of oscillation and to disengage said resilient member after said angular displacement to break electrical contact between said wedge and said resilient member before electrical contact is

broken between said resilient member and said contactor member.

4. In an apparatus for calibrating time indicating devices, an oscillating member, a deflecting wedge attached and electrically connected thereto and comprising one leg of a trigger circuit of a flash lamp energizing circuit, a resilient member adjacent said oscillating member, and a contactor member adjacent said resilient member and comprising the other leg of said trigger circuit; said resilient member and said contactor member normally forming part of an open circuit; said deflecting wedge disposed to engage said resilient member in a period of maximum angular speed of said oscillating member and adapted to deflect said resilient member away from said contactor member during one half-cycle and to deflect said resilient member to momentarily touch said contactor member during a predetermined angular displacement of said oscillating member in the other half-cycle of oscillation of said oscillating member to complete the said trigger circuit from said oscillating member through said wedge, said resilient member and said contactor member to trigger said flash lamp energizing circuit and momentarily illuminate an instrument to be calibrated in response to said alternate half-cycles of oscillation and to break the electrical circuit between said wedge and said resilient member after said predetermined angular displacement of said oscillating member before electrical contact is broken between said resilient member and said contactor member.

5. In an apparatus for calibrating time indicating devices, an oscillating member, spring means for storing power to impart oscillatory motion thereto, a deflecting wedge attached and electrically connected to said oscillating member and comprising one leg of a trigger circuit of

a flash lamp energizing circuit, a resilient member adjacent said oscillating member, and a contactor member adjacent said resilient member and comprising the other leg of said trigger circuit; said resilient member and said contactor member normally forming part of an open circuit; said deflecting wedge disposed to engage said resilient member in a period of maximum angular speed of said oscillating member and adapted to deflect said resilient member to momentarily touch said contactor member during a predetermined angular displacement of said oscillating member in alternate half-cycles of oscillation of said oscillating member and close a trigger circuit of a flash lamp energizing circuit from said oscillating member through said wedge, said resilient member and said contactor member and momentarily illuminate an instrument to be calibrated in response to said alternate half-cycles of oscillation and to break the electrical circuit between said wedge and said resilient member after said predetermined angular displacement of said oscillating member before electrical contact is broken between said resilient member and said contactor member.
